SPRING TENSION COVER FOR A FOOD MOLD

Richard A. Hawley, Oakland, and Harold B. Hanson, San Leandro, Calif., assignors to Meat Packers Equipment Co., Oakland, Calif., a corporation of California

Filed June 17, 1963, Ser. No. 75,366

Term of patent 14 years

(Cl. D58—26)

FIG. 1.

FIG. 2.

FIG. 3.

FIG. 4.

FIG. 5.

FIG. 6.

FIG. 1 is a perspective view of a spring tension cover showing my new design; the broken line showing of a food mold being for purposes of illustration only.

FIG. 2 is an enlarged perspective view of the spring tension cover.

FIG. 3 is a top plan view thereof.

FIG. 4 is a side elevational view.

FIG. 5 is a bottom plan view.

FIG. 6 is an end elevational view.

We claim:

The ornamental design for a spring tension cover for a food mold, as shown and described.
